UNITED STATES PATENT OFFICE.

WILLIAM F. KRONE, OF ST. LOUIS, MISSOURI.

ENVELOP.

1,150,524.

Specification of Letters Patent. Patented Aug. 17, 1915.

Application filed January 29, 1915. Serial No. 5,035.

To all whom it may concern:

Be it known that I, WILLIAM F. KRONE, a citizen of the United States, residing at the city of St. Louis, State of Missouri, have invented a certain new and useful Improvement in Envelops, of which the following is a specification, reference being had to the accompanying drawings, forming a part thereof.

10 This invention relates to a certain new and useful improvement in envelops, the object of my invention being to provide an envelop, especially adapted and designed for employment in railroad business and the like, which 15 may be economically and conveniently used repeatedly for the carrying of orders, despatches, communications, or other papers to and between different designated departments or addressees located in the same or 20 different towns or other places.

With the above and other objects in view, my present invention resides in certain novel features of form, arrangement, construction, and combination of parts, all as will herein- 25 after be described and afterward pointed out in the claims.

In the accompanying drawings, which show my invention in preferred form, Figure 1 is a front elevational view of an envelop embodying my invention; Fig. 2 is a rear elevational view of the same; Fig. 3 is a transverse sectional view through the same on the line 3—3, Fig. 1; and Fig. 4 is a transverse sectional view through the same 35 on the line 4—4, Fig. 2.

Referring to the said drawings, in which like reference characters refer to like parts throughout the several views, A indicates the envelop proper, which is preferably 40 formed from a sheet of paper or other suitable flexible material folded lengthwise upon itself to provide a rear wall 1, a front wall 2, and a flap or extension 3 on front wall 2 foldable in the finished envelop, to retain the 45 contents of the envelop, either down over and upon rear wall 1, as shown, or into the body of the envelop between walls 1 and 2, as will be understood. At one or the right-hand end of the envelop, reference being had to Fig. 1, front wall 2 is provided with an extension 4, which is folded over and upon rear wall 1 and glued or otherwise fastened thereto, so as to permanently close that end of the envelop. At the opposite 50 or left-hand end of the envelop, both walls 1

and 2 are provided with extensions 4'—4', which are also folded over and upon rear wall 1 and glued or otherwise fastened thereto, so as not only to permanently close that end of the envelop, but also to reinforce and 60 strengthen walls 1 and 2 at said end of the envelop.

As seen in Fig. 1, a portion of the front face of wall 2 of envelop A is divided by preferably a plurality of parallel lines 5 into a vertical column or plurality of printing or address-spaces 6 extending preferably lengthwise of the envelop, in each of which spaces is printed or otherwise inscribed to permanently appear upon the envelop A the 70 name of a particular town, city, or other address B, as may be desired, I having employed as addresses in the present instance the names of certain towns or cities. It will be understood that the number of such 75 spaces 6 and correspondingly the number of addresses B may vary, as desired, depending upon the work in which the envelop is to be used, as well as also upon the size of the particular envelop. Also printed or other- 80 wise permanently appearing in a vertical column upon the front face of wall 2 of the envelop A, to the left of addresses B, are the names, designations, titles, or the like of a plurality of addressees C. For purposes of 85 illustration, I have in the present instance used the titles or designations of certain railroad officials. As seen clearly in Fig. 1, one or more addressees C are in alinement with each address-space 6, within which 90 space appears a particular address B, the addressees C of, or corresponding to, a certain address B being preferably, as shown, bracketed to the particular address B.

Provided in walls 1 and 2 of envelop A 95 preferably to the left of addressees C and through said reinforced or strengthened portion of said walls, is a plurality of suitable perforations or the like D arranged also in a vertical column or columns, there being 100 one perforation D for, and in alinement with, each particular addressee C. The number of perforations D accordingly de- 105 pends upon the number of addressees C ap- pearing permanently upon the envelop A, the perforations D, when in more than one column, being preferably staggered, for pur- poses of convenience and to save space with- in the size or limits of the envelop.

Adapted to be removably passed through 110

the perforations D and to be releasably engaged with the envelop A, is a so-called paper-fastener or other suitable addressee-indicating member E. This member E is 5 designed to be employed with envelop A to indicate the particular addressee C to whom the envelop A, with its then contents, is addressed, this member E, in the use of the envelop A, being passed by the user thereof 10 through the particular perforation D in front of the particular addressee C to whom it may be desired that envelop A shall next go. Thus, by passing member E in turn and interchangeably through respective or different perforations D, the envelop A may be 15 readily and quickly properly directed to the proper addressee, whereby, as will be obvious, envelop A may be conveniently used repeatedly until entirely worn out, a great 20 economy being thereby effected.

Should it be desired to employ envelop A in sending papers, communications, or the like to an addressee whose name or designation does not appear permanently upon 25 the envelop with permanent addressees C, envelop A is further provided in its front wall 2 with an enlarged or cut-away portion, as at F, the name or designation of the particular addressee in such event appearing 30 through said opening upon the contents of the envelop. Envelop A is further provided with an additional perforation D' in alinement with said opening F, through 35 which perforation said member E is also adapted to be passed to indicate, as may then be required, the addressee of the envelop.

I am aware that minor changes in the 40 form, arrangement, construction, and combination of the several parts of my new envelop may be made and substituted for those herein shown and described without departing from the nature and spirit of my invention. As shown in Fig. 1, additional 45 matter or information may appear upon the face of the envelop A, if desired.

Having thus described my invention, what I claim and desire to secure by Letters Patent is:

50 1. An envelop of flexible material for containing and carrying correspondence, papers, and the like, said envelop bearing permanently upon its face a plurality of fixed addresses, and an indicating-member 55 for directing the envelop to any particular one of said addresses, said member being interchangeably usable with all said addresses and being removably detachable

from the envelop when indicating any particular one of said addresses. 60

2. An envelop of flexible material for containing and carrying correspondence, papers, and the like, said envelop bearing permanently upon its face a plurality of fixed addresses, and an indicating-member 65 for directing the envelop to any particular one of said addresses, said member being interchangeably usable with all said addresses and extending removably through, and being detachably engaged with, the envelop when indicating any particular one of said addresses. 70

3. An envelop of flexible material for containing and carrying correspondence, papers, and the like, said envelop bearing 75 permanently upon its face a plurality of fixed addresses and being transversely provided with a plurality of perforations in alinement respectively with said addresses, and an indicating-member for directing the 80 envelop to any particular one of said addresses, said member being interchangeably usable with all said addresses and extending removably through the particular alining perforation, and being detachably clenched 85 upon the envelop, when indicating any particular one of said addresses.

4. An envelop of flexible material for containing and carrying correspondence, papers, and the like, said envelop being 90 transversely provided with a plurality of perforations and having a portion of its face divided into a plurality of address-spaces, a plurality of fixed addresses permanently upon the face of said envelop 95 within said spaces respectively, a plurality of fixed addressees also permanently upon the face of said envelop to the left of said addresses, more than one of said addressees being in alinement with said spaces respectively and said perforations being in alinement with said addressees, and an indicating member for directing the envelop interchangeably to any particular one of said fixed addressees, said member being adapted 100 to be passed through the perforation in alinement with said particular addressee and detachably clenched upon the envelop. 105

In testimony whereof, I have signed my name to this specification, in the presence 110 of two subscribing witnesses.

WILLIAM F. KRONE.
